UNITED STATES PATENT OFFICE.

EDWARD M. SHREINER, OF CANTON, OHIO.

BILL-FILE.

No. 920,402.

Specification of Letters Patent.

Patented May 4, 1909.

Application filed October 20, 1908. Serial No. 458,590.

To all whom it may concern:

Be it known that I, EDWARD M. SHREINER, a citizen of the United States, residing at Canton, in the county of Stark and State of Ohio, have invented a new and useful Improvement in Bill-Files, of which the following is a specification.

The invention relates to a file for bills of sales or accounts, as of a retail merchant, and the object of the invention is to provide a simple, compact and inexpensive file in which the loose bills of respective customers can be separately stored, and in which the file proper is normally arranged in a rectangular form and can be readily placed on and removed from its support, for entering in a safe or vault, and when supported is in convenient position for entering accounts as sales are made or goods are delivered. These general objects and other particular advantages are attained by making the file proper of a series of thin trays provided with pairs of longitudinally elongated slots near their upper ends, and having series of index tongues on opposite sides of alternate sheets and arranged in echelon on each side of the file; and by providing a pair of hinged arms on the supporting bracket, each arm being reversely curved first rearward and then forward from the hinge toward its free end, which arms are adapted to be entered into the elongated slots of the trays for holding the same during the ordinary use of the file, whereby the trays are adapted to be individually and collectively rotated upward and backward, and to be held and supported by the free ends of the arms when rotated backward beyond a vertical position.

A further object of the invention pertains to the particular method of securing together the two plates of the supporting bracket, which object is attained by providing a fixed post and a removable pin on one section and by providing an aperture on the other section adapted to pass over the head of the post, with a slot extending in one direction from the aperture adapted to receive the shank of the post and a slot in the opposite direction adapted to receive the shank of the pin.

A supplemental feature of the invention relates to means for supporting the open trays when they are inclined forward from a vertical position, which purpose is accomplished by providing a post behind the file

having a hinged finger thereon with a hook on its free end adapted to be engaged under the free ends of the trays.

The invention, thus described in general terms, is illustrated in the accompanying drawings, forming part hereof, in which—

Figure 1 is a perspective view of a shelf with a number of files in various positions thereon or adjacent thereto; Fig. 2, a detached perspective view of the supporting bracket showing its parts separated one from another; Fig. 3, a detached perspective fragmentary view showing the hinged parts of the supplemental supporting post and finger; Fig. 4, a detached perspective view of one tray; and Fig. 5, a longitudinal section of the bill file showing the operation of the same, without the supplemental supporting means.

Similar numerals refer to similar parts throughout the drawings.

The file proper is composed of the trays 1^a, 1^b, 1^c, etc., which are preferably made of thin metal sheets with series of perforations 2 in the body to lessen the weight of the individual trays and of the file as a whole. Each tray is provided with one or more longitudinally elongated slots 3 at or near the normal rear end, and the side and forward edges 4, 4^a and 5 are flanged diagonally upward and outward. The trays are normally adapted to nest together in a rectangular pack, as shown by broken outlines in Fig. 5, and the bills 6 are stored between the respective trays, being there held by the weight of the superimposed trays and by the flanged edges 90 of the particular tray in which the bills are filed.

The index tongues 7^a, 7^b, 7^c, etc., are provided on the edges of one side flange 4^a of the several trays, which tongues are arranged on opposite sides of alternate trays, the tongues on each side of the file being arranged in echelon, and index reference letters as A, B, C, etc., are marked on the upwardly exposed faces of successive tongues. The normal top tray 1^a is preferably provided with the index card 8 which is preferably held in position by the edges 9, 9^a and 10 of the side and end flanges which are bent over corresponding edges of the card, and on this card are listed the names pertaining to the series of bills or accounts included in the file, each name being indexed with a letter like the index letter contained on the corresponding tray tongue.

It is evident that to expose the bills of a certain account, it is only necessary to locate the tongue which is formed on the flange of the tray next above the account, and by placing the finger under the end of this tongue which projects beyond the tongue next below the superimposed trays can be readily separated from the lower ones and lifted to uncover the desired bills.

10 The supporting bracket is preferably composed of two interengaging plates 11 and 12, the rear portion 11^a of the former plate being fastened as by the screws 13 to the shelf 14 and the forward portion 11^b of this fixed plate being preferably inclined downward and forward from the forward end of the shelf. The post 15 having the head 15^a thereon, is provided on the forwardly inclined portion of the fixed plate, and the 20 aperture 16 is also provided in this plate adjacent to the post.

The aperture 17 is provided in the plate 12, preferably near its rear end and in the middle line thereof, which aperture is shaped 25 to pass freely over the head of the post 15. The aperture 17 is extended, preferably rearward, by the relatively narrow slot 17^a, and forward, by the similar slot 17^b, one of which slots, preferably the rear one, being 30 adapted to neatly receive, by a forward sliding of the plate 12, the shank of the post 15 and to be engaged under the head thereof, in which relation of the parts the other slot, preferably the forward one, registers with 35 the aperture 16 of the fixed plate. The shank of the headed pin 18 is then entered through the forward slot 17^b and into the aperture 16 of the fixed plate, which slot and aperture the pin is arranged to neatly 40 fit, whereby the two plates are positively locked in their engaged position.

The parallel arms 19 are preferably yoked together by the pintle 20 which pintle is adapted to rotate in the transversely positioned bearing 21 preferably located on 45 the rear end of the detachable plate 12. Referring to the upright position of these arms, illustrated by broken lines in Fig. 5, they are reversely curved upward from the 50 hinged end, first rearward and then forward, and in this position they are adapted to receive the file proper by being entered through the elongated apertures of the respective trays. While the use of two arms is illustrated and preferred, it is not intended to 55 limit the scope of the invention either to a particular number or to a plurality of arms. When the trays are thus engaged on the parallel arms, the elongation of the tray 60 slots permits considerable freedom of movement of the trays on the arms which freedom permits the trays to hang slightly forward on the arms as illustrated for the closed files in Fig. 1, or to be rotated upward and 65 backward as illustrated for the upper trays

in Fig. 5; these movements of the trays being permitted by the rotation of the arms on the hinge formed by the pintle in its bearing.

It is evident that when the trays hang 70 forward on the arms, they are securely held and bound together by the abutting action of the forward free ends 19^a of the arm as shown in Fig. 1, and that when the trays are rotated upward and backward beyond 75 the vertical position, they are securely held and supported in the backwardly inclined position by the abutment of the same free ends of the arms as shown in Fig. 5. And it is evident that when the arms are brought 80 to an upright position, the trays are nested in substantially a rectangular pack, as shown by broken outlines in Fig. 5, and that in this relation they can be readily removed from the bracket and its arms, by lifting the trays 85 directly upward. Furthermore, when desired, the trays and the detachable part of the back can be readily detached from the fixed plate thereof by merely removing the locking pin.

The supplemental posts 22 are preferably provided on the shelves a sufficient distance in the rear of the files to clear the trays when they are rotated upward and backward beyond a vertical position. These posts are 95 curved upward and forward to clear the locus of the upper edges of the trays as they are rotated backward, and on the upper end of each post is hinged the finger 23 having the hook 24 on its free end. The hooked 100 fingers are adapted to be rotated forward to engage and hold the free ends of the trays when they are opened upward to a position inclined forward from the vertical, as shown for the open file in Fig. 1, or the hooked 105 fingers can be rotated backward out of the way when not in such use; and it will be understood that these supplemental posts and hooked fingers can be dispensed with altogether, in which event the file is operated 110 exclusively as shown in Fig. 5.

What I claim as my invention, and desire to secure by Letters Patent, is—

1. In combination, a series of normally nested trays having upwardly inclined flanges on their sides and forward end and longitudinally elongated slots in their rear end, and a bracket including an inclined plate with parallel arms yoked together and hinged to the rear part of the plate, the arms 11 being reversely curved upward first rearward then forward and being entered through the slots, whereby the trays are adapted to be opened rearward and closed forward on the bracket and to be held and supported there- 12 by in the opened and closed positions.

2. In combination, a series of normally nested trays having longitudinally elongated slots in their rear ends, and a bracket with parallel arms yoked together and hinged 13

thereon, the arms being reversely curved upward first rearward then forward and being entered through the tray slots, whereby the trays are adapted to be opened rearward and closed forward on the bracket and to be held and supported thereby in the opened and closed positions.

3. In combination, a series of normally nested trays having longitudinally elongated slots in one end, and a bracket with parallel arms yoked together and hinged thereon, the arms being reversely curved in vertical-longitudinal planes and being entered through the tray slots, whereby the trays are adapted to be rotated to and fro on the bracket and to be held and supported by the arms at each end of their movement.

4. In combination, a series of normally nested trays having a longitudinally elongated slot in one end, and a bracket having an arm hinged thereon, the arm being reversely curved in a vertical-longitudinal plane and being entered through the tray slots, whereby the trays are adapted to be rotated to and fro on the bracket and to be held and supported by the arm at each end of their movement.

5. In combination, a series of normally nested trays having tongues on opposite sides of alternate trays, the tongues on each side being arranged in echelon and having index designations on their exposed upper sides and a card on the normal top tray having an index thereon with corresponding

designations located opposite the respective 35 tongues.

6. In combination, a series of normally nested trays having tongues on opposite sides of alternate trays, the tongues on each side being arranged in echelon, and having 40 index designations on their exposed upper sides, the exposed lower sides of the tongues being adapted to be engaged for lifting the superimposed trays from the ones below.

7. In combination, a shelf or the like having a plate attached thereon, there being a post having a head on the shelf-plate and an aperture in the plate adjacent to the post, a bill file including a bracket plate having an aperture therein adapted to pass freely over 50 the post head and relatively narrow slots on opposite sides of the same aperture, one slot being adapted to neatly receive the post-shank and in this relation the other slot being arranged to register with the shelf-plate aperture, and a pin adapted to be entered and fit in the latter slot and aperture, whereby the plates are engaged and locked together.

8. In combination, a series of trays normally nested together and adapted to be rotated upward on one end, and an adjacently pivoted finger having a hook thereon adapted to engage and support the free ends of the trays when in an elevated position.

EDWARD M. SHREINER.
